RAIL FASTENING

Leonard C. Peskin and Harvey R. Rice, Worcester, Mass., assignors to The American Steel and Wire Company of New Jersey, a corporation of New Jersey

Application October 31, 1936, Serial No. 108,668

4 Claims. (Cl. 238—349)

This invention relates to rail fastenings, and is particularly concerned with that type utilizing a spring metal rail-clip having its ends arranged to respectively press downwardly on the top of the base of the rail to be fastened and the top of the tie-plate ordinarily carrying this rail. Such a clip usually functions as a cantilever spring whereby the pressure that it can apply to the top of the base of the rail is limited. The present invention is intended to provide for the application of greater pressure to the top of the base of the rail than is possible in the case of such a clip, while retaining the simplicity resulting from the use of the latter. The fastener constructed according to the principles of the present invention possesses other advantages which will become apparent from the following.

An example of the invention is illustrated by the accompanying drawing, in which:

Figure 1 is a plan of a rail fastening embodying the features of the present invention.

Figure 2 is a cross-section.

Figures 3 through 5 are, respectively, plan, elevation and perspective views of details.

A tie-plate 1 of the usual construction, having spike holes 2, carries the rail 3 to be fastened. The holes 2 are, of course, formed, at least in some instances, so as to be at least adjacent the edge of the base of the rail 2.

The clip 4 is made of spring metal and is of an elongated U-shaped form. It is particularly characterized by being arched continuously throughout its length. That is to say, no portion of the clip is straight or reversely curved so as to function as a cantilever spring, the idea being that the clip should function as an arch whereby both its ends must spring when either is stressed. The legs of this clip are outwardly offset, as at 5, to provide a rectangular opening 6. The clip is shown with its closed end resting on the top of the tie-plate, but this is merely for illustrative purposes. If desired, wedges or bearing plates may be inserted between the ends of the clip and the elements against which they press.

Pressure is applied to the top of the clip 4 by a bolt 7 having a hooked end 8 which may be inserted through one of the spike holes 2 and hooked beneath the bottom of the plate 1. This bolt has a threaded end 9 and its shank is rectangular so as to fit the opening 6 provided by the offsets 5 in the legs of the clip 4. The end 8 may be made so that a conventional tie-plate may be used, it being remembered that four spike holes are ordinarily provided whereby two may

be used to fasten the plate to the tie by means of spikes.

A nut 10 is provided for the bolt 7, this nut being adapted to be screwed upon the threaded end 9 of the latter. Because of the position of the opening 6, this applies pressure to the mid-portion of the arched clip 4.

As a safeguard against loosening of the nut 10, a washer 11 is inserted between this nut and the clip. This washer is in the form of a flat rectangle having an opening 12 that fits the rectangular shank of the bolt 7 and depending flanges 13 that embrace the edges of the offsets 5 in the legs of the clip 4. Furthermore, a rib 14 is formed in the top of this washer while a correspondingly shaped depression 15 is formed in the bottom of the nut 10. The rib 14 and depression 15 are constructed to provide rounded surfaces whereby forceful turning of the nut 10 can cause disengagement of this rib and recess 15 upon springing of the clip 4.

When a wheel passes over the rail 3 in such a manner as to cause upward deflection of the latter, both ends of the clip 4 exert a springing action. If necessary, the bolt 7 can pivot slightly about its hooked end 8 to equalize the stresses involved. It is obvious that there is no danger of the nut 10 becoming loose in service. Finally, due to the arched construction of the clip 4 and the central application of the pressure to this clip, more pressure can be applied to the top of the base of the rail 3 than can be done by means of a spring clip functioning as a cantilever spring. It is taken for granted that the reader will understand that the hooked end 8 of the bolt 7 can be accommodated by slightly notching the top of the tie beneath the plate 1.

We claim:

1. A rail fastening including a tie-plate for carrying the rail to be fastened and in which a hole is formed so as to be at least adjacent the edge of the base of said rail, an elongated U-shaped spring metal rail clip that is arched throughout its length and has its legs offset outwardly at least adjacent its middle to provide a rectangular opening, one end of said clip being adapted to press downwardly on the top of the base of said rail and its other end being adapted to press downwardly on the top of said plate, a bolt having a hooked lower end adapted to be inserted through said hole and hooked into engagement with said plate, said bolt having a threaded upper end and a rectangular shank adapted to fit through said opening of said clip, a nut for said upper end of said bolt and a flat washer for in-

- section between said clip and said nut and having flanges adapted to embrace the outside of the legs of said clip, the adjacent surfaces of said nut and said washer providing interfitting projections and depressions which can be disengaged upon forced rotation of said nut and springing of said clip.
2. A rail fastening including an elongated upwardly arched U-shaped spring metal clip for holding a rail down on suitable support and having its legs offset outwardly at one portion to provide a fastening element passage and a fastening element adapted to pass through said passage and apply downward pressure on said clip.
3. A rail fastening including an elongated upwardly arched U-shaped spring metal clip for holding a rail down on suitable support and having its legs offset outwardly at one portion to provide a fastening element passage and a fastening element adapted to pass through said passage and apply downward pressure on said clip, said fastening element having a non-circular shank portion and said passage provided by said offset legs being shaped to fit said shank portion.
4. A rail fastening including a tie-plate for carrying the rail to be fastened and in which a hole is formed so as to be at least adjacent the edge of the base of said rail, an elongated upwardly arched U-shaped spring metal rail clip that has its legs offset outwardly to provide a rectangular opening, one end of said clip being adapted to press downwardly on the top of the base of said rail and its other end being adapted to press downwardly on the top of said plate, a bolt having a lower end adapted to be inserted through said hole in engagement with said plate, said bolt having a threaded upper end and a rectangular shank adapted to fit through said opening of said clip, a nut for said upper end of said bolt and a flat washer for insertion between said clip and said nut and having flanges adapted to embrace the outside of the legs of said clip, the adjacent surfaces of said nut and said washer providing interfitting projections and depressions which can be disengaged upon forced rotation of said nut and springing of said clip.
